SANITARY GARBAGE RECEPTACLE.
APPLICATION FILED JUNE 7, 1912.

Patented Apr. 7, 1914.

2 SHEETS—SHEET 2.

UNITED STATES PATENT OFFICE.

SOLOMON I. SEGALL, OF NEW YORK, N. Y.

SANITARY GARBAGE-RECEPTACLE.

1,092,752.

Specification of Letters Patent.

Patented Apr. 7, 1914.

Application filed June 7, 1912. Serial No. 702,202.

To all whom it may concern.

Be it known that I, SOLOMON I. SEGALL, a citizen of the United States, and a resident of the city of New York, borough of Brooklyn, in the county of Kings and State of New York, have invented a new and Improved Sanitary Garbage-Receptacle, of which the following is a full, clear, and exact description.

10 This invention relates to storage receptacles, and particularly to receptacles designed to store garbage, trash, and the like, and has for an object to provide an improved structure which will automatically 15 close itself after each time the same is opened.

20 A further object of the invention is to provide a receptacle having a disinfectant dispensing means arranged therein and co- 25 acting with the lid of the receptacle for dispensing or discharging a predetermined amount of disinfectant each time the lid is opened, the disinfectant dispensed being of any desired kind.

25 In carrying out the objects of the invention, a receptacle of a proper size for receiving the can is provided, having a can-receiving compartment and a lid-receiving compartment, the can or lid in the receptacle being inserted or removed through a suitable door. Arranged back of the can-receiving compartment is a liquid or disinfectant-receiving compartment designed to receive one end of an atomizer which is operated each time the lid of the receptacle is opened. In order to accomplish this result 30 a collapsible pneumatic bag is provided arranged in the path of movement of an extension on the lid to be collapsed thereby 35 and thus force air through the atomizer each time the lid is opened, whereby a certain quantity of the disinfectant is discharged, a suitable discharge nozzle being provided 40 for directing the disinfectant into the can in the can-receiving compartment.

45 A practical embodiment of the invention is represented in the accompanying drawings forming a part of this specification, in which similar characters of reference indi-

cate corresponding parts throughout all the 50 views.

Figure 1 is a front view of an embodiment of the invention; Fig. 2 is a section through Fig. 1 approximately on line 2—2; Fig. 3 is a section through Fig. 2 approximately on line 3—3; and Fig. 4 is a section through Fig. 2 on line 4—4.

Referring to the accompanying drawings by numeral, 1 indicates a housing formed of any desired material, preferably zinc or 60 sheet iron properly galvanized. The housing 1 is provided with a door 2 which permits the can 3 to be properly inserted and removed, as well as the lid 4, compartments 5 and 6 being provided for the can and lid, 65 respectively. At the rear of the compartment 5 is a third compartment 7 designed to receive a disinfecting fluid 8 and the feeding tube 9 of an atomizer 10. The atomizer 10 is secured to a cover 11' by 70 threads or in any desired manner so as to be held rigidly in position. A removable discharge nozzle 12 is connected with the atomizer 10 so as to direct the fluid 8 into the can 3, while a rigidly secured pipe 13 75 extends from the opposite side for causing communication between the atomizer and the pneumatic bag 14. A coupling 15 is provided in the pipe 13 so that the bag 14 may be disconnected from the pipe 13 at 80 any time. When the coupling 15 is disconnected and the nozzle 12 is removed the atomizer may be unfastened and removed from the plate 11.

85 The bag 14 rests upon a shelf 16 connected in any desired manner to the side plates 17 and 18 and to an upstanding flange 19 projecting from the plate 11. In order to properly position the bag 14 a slot or opening 20 is provided whereby the bag 90 may be positioned centrally of the shelf 16.

95 The presser plate 21 is provided with a rubber facing 22 which is adapted to cover the eyelets 23 and 24 before beginning the collapsing action of the bag. These eyelets could be made in the form of valves, if desired, although ordinarily such will not be necessary, as the rubber 22 will seal the eye-

lets against the escape of air. When the bag is collapsed the air will be forced through the atomizer and consequently cause a discharge of the disinfecting fluid 8. Upon releasing the bag 14 the same will automatically expand to the position shown in Figs. 2 and 4, the air being permitted to pass through the eyelets into the bag and the bag being of such a construction as to automatically resume its original shape.

The atomizer 10 may be of any desired or usual construction, but for the purpose of illustration the same is shown with the body portion 40 having passageways 41 and 42 provided therein, the passageway 42 communicating with the interior of the tank or receptacle 7 and with the bag 14 through members 13 and 15. The aperture 41 communicates with pipe 9 and with the discharge member 12 so that when air is forced through bag 14 downward into the tank 7, a corresponding quantity of liquid 8 will be forced upwardly through pipe 9 and out the discharge member 12.

The presser plate 21 is a bent over portion of an extension from the door or lid 26 which is pivotally mounted at 27 and 28 to the upper part of the side walls of the housing 1. Reinforcing bars 25 and 32 brace the sheet metal portion of the door and also the presser plate construction 21 so that when the door is open and the presser plate is caused to press against the pneumatic bag 14 the structure will be sufficiently strong for accomplishing the purpose desired. The door 26 is provided with an overhanging portion 29 designed to fit over an inwardly turned flange 30 of the housing whereby a tight joint is provided. Arranged near the lower edge of the door 26 is a handle 31 formed of iron, or some other comparatively heavy material of an appreciable size, which will cause the door to automatically move downwardly, or to a closed position as shown in Fig. 2. Any desired number of braces 32 may be provided for bracing the door and properly holding the same in position.

In forming the housing 1, the chamber or compartment 5 is divided from the upper chamber 33 by the plate 11, which is formed with an aperture 34 through which the garbage and other matter are passed into the can 3. In order to prevent anything from missing the aperture 34 a pair of up-standing side flanges 35—36 are arranged at the sides of the aperture 34 while the upstanding flange 19 is arranged at the back.

In order to have access to the bag 14 and associated parts, including the compartment 7, a removable portion 37 is provided for the chamber 33, the same being hinged at 38 and provided with an overhanging flange 39 for insuring a tight joint. By providing the

removable portion 37 an inspection or repairs may be made to the various parts and also the compartment 7 may be refilled. At the opposite end of the end to which the flange 39 is placed is an overlapping flange 40 extending upwardly from the plate 11. In connection with the plate 11 it will be observed that the same extends from one wall to the other of the housing 1 and provides a top for the compartments 5 and 7, so that the one passageway or means of communication between the compartments 5 and 7 and the chamber 33 is through the aperture or opening 34 and through the aperture in which the end of the atomizer 10 is positioned.

In operation, after the various parts have been arranged as shown in Fig. 2, and it is desired to place garbage or other matter in the can 3, the lid 26 is raised until the presser plate 21 collapses the bag 14. This will cause a certain amount of the disinfecting fluid 8 to be sprayed into the can 3. The garbage or other matter is then admitted through the aperture 34 into the can 3 and the lid 26 is permitted to automatically close. The next time anything is to be placed in the can 3 the lid 26 is again opened and the operation is repeated. In this way each layer of matter placed in the can receives a certain amount of disinfecting fluid 8. It will be evident, of course, that if the lid was opened without placing any matter in the can 3 several layers of disinfecting fluid could be provided.

Having thus described my invention, what I claim as new and desire to secure by Letters Patent is:—

1. In a device of the character described, a housing formed with a lower part and an upper part, said lower part comprising a can receiving chamber and a liquid receiving chamber, said upper part comprising an entrance hood formed with a pivotally mounted door having an extension arranged thereon and with a flooring structure provided with an aperture therein, said flooring structure being formed with a substantially surrounding upstanding wall for guiding matter through said aperture, and means actuated by the extension on said door for directing liquid from said liquid receiving chamber to said can receiving chamber.

2. In a device of the character described, a housing provided with a can-receiving chamber, a liquid-receiving chamber, an atomizer associated with said liquid-receiving chamber and formed with a discharge member adapted to discharge liquid into said can-receiving chamber and a pneumatic bag for supplying air to said discharge member, said pneumatic bag being formed with a pair of eyelets, a swinging door for said housing, said bag being arranged in the path of move-

ment of said door, a presser arranged on
said door formed with a resilient covering
member designed to engage and cover the
eyelets in said bag when said door has been
5 moved, whereby said bag will be collapsed
by said presser upon each opening of said
door to its fullest extent for causing air to
be forced into said discharge member.

In testimony whereof I have signed my
name to this specification in the presence of 10
two subscribing witnesses.

SOLOMON I. SEGALL.
